(57) CLAIM

The ornamental design for coffee pot, as shown and described.

DESCRIPTION

FIG. 1 is a perspective view of embodiment one of the coffee pot.

FIG. 2 is a side view thereof, the opposite side is a mirror image thereof;

FIG. 3 is a top view thereof.

FIG. 4 is a perspective view of embodiment two of the coffee pot.

FIG. 5 is a side view thereof, the opposite side is a mirror image thereof; and,

FIG. 6 is a top view thereof.

The second embodiment of the coffee pot design is symmetrical on each side. The back is un-ornamented. The trademarks Cali and White Brown are not part of the design application.
